UNITED STATES PATENT OFFICE.

CHRISTIAN AALBORG, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTING DEVICE.

1,181,200.

Specification of Letters Patent. Patented May 2, 1916.

Application filed July 23, 1913. Serial No. 781,739.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Circuit-Interrupting Devices, of which the following is a specification.

My invention relates to circuit interrupters and particularly to knife blade switches of the double throw quick-break type, and it has for its object to provide a double-throw quick-break knife blade switch of strong but inexpensive construction.

Heretofore the quick-break members of double-throw knife-blade switches have been pivoted at different points on the main knife blade and have been yieldingly held against the main knife blade by springs. This required a plurality of holes in the main knife blade and necessitated the use of at least two springs on each of its sides. As heretofore provided, the quick-break knife blades were of a solid structure and, consequently, the hinged or angular portions required complicated machining. In my invention, I provide an easily constructed double-throw quick-break knife-blade switch that requires only one pivot member for pivoting the quick-break knife blades. Since the springs, as provided in my device, need not be attached to the main knife-blade, the construction may be so simplified as to permit of easy and quick repair.

I further provide a construction, independent of the springs, for limiting the travel of the quick-break knife blades from their initial positions adjacent to the main knife blade.

Figure 1 of the accompanying drawing is a plan view of a quick-break knife blade before it is bent into its final form. Fig. 2 is a side elevation of a completed blade. Fig. 3 is a front elevation of the completed blade and Fig. 4 is a side elevation of a complete double-throw quick-break knife-blade switch embodying my invention.

Referring to the drawing, my invention comprises a main blade 1 of a double-throw knife-blade switch, a member 2 to which the blade 1 is pivoted and stationary contact members 3 and 4, all of which are mounted on a base 5. Each of the auxiliary quick-break blades 6 and 7 is formed

from a flat piece of metal 8, as shown in Fig. 1, by folding it laterally on a line I—I to provide two arms 9 and 10 of unequal length, the arm 9 having a hole therein to receive a pin 11 for pivoting it to the main blade 1. The arms 9 and 10 are spaced apart to embrace the blade 1 and the walls 12, formed at their junctions with the body portions are inclined at such angles as to constitute stops for engaging the corresponding edges of the main blade when moved outwardly to the allowable degree. The quick-break blades 6 and 7 are located at opposite edges of the main blade 1 so that only one pivoting pin is required. The respective ends of a spring 13 are attached to pins 14 and 15 that project laterally from the sides of the members 6 and 7, a second spring (not shown) being similarly connected to the other sides of the quick-break knife blades to hold them yieldingly against the main blade.

The operation of my invention is obvious to any one skilled in the art, and its advantages will be readily understood. When a quick-break blade snaps out of its stationary contact terminal, it pivots around the pivotal point 11 on one of its arms, being guided by the rounded part of the other arm. The action of the quick-break blade is similar to other quick-break blades in that the main blade, when withdrawn, leaves the quick-break blade in contact, until the main blade has traveled such a distance that the spring 13 overcomes the friction with the stationary contact terminal or until the inclined portion 12 engages the main blade to force the auxiliary blade out of engagement with the contact terminal.

Minor variations as to the size, shape and arrangement of the various parts may be made within the scope of the appended claims without departing from my invention.

I claim as my invention:

1. In a circuit-interrupting device, the combination with contact jaws and a double-throw knife-blade member, of an auxiliary quick-break knife-blade member at each edge thereof and attached thereto by a single means, said quick-break knife-blade members severally comprising a folded metal piece having laterally projecting arms of unequal length provided with

rounded ends, the said arms being of such length that the rounded ends serve as bearings.

2. In a circuit-interrupting device, the combination with contact jaws and a main double-throw knife-blade member, of quick break blades attached to said main member and severally comprising a metal piece having arms of unequal length, said arms being provided with rounded ends that constitute bearings for each other.

3. In a circuit-interrupting device, the combination with contact jaws and a main double-throw knife-blade member, of quick-break blades attached to said main member at a single point and severally comprising a metal piece having arms of unequal length, said arms being provided with rounded ends that constitute bearings for each other.

4. A double-throw knife-blade switch comprising a main knife-blade member and two quick-break blades attached thereto at a single point, said quick-break blades sev-

erally comprising a metal piece having two arms of unequal length provided with rounded ends, the rounded ends of the arms on one blade being adapted to constitute the bearings of the other blade.

5. A double-throw switch comprising a main knife-blade member, two quick-break blades and means interposed between the quick-break blades for normally holding them adjacent to the said main blade, said quick-break blades severally comprising a metal piece having two arms of unequal length provided with rounded ends, the rounded ends being adapted to constitute bearings.

In testimony whereof, I have hereunto subscribed my name this 24th day of July, 1913.

CHRISTIAN AALBORG.
